FIG. 2.

FIG. 1.

Inventor
ALFRED E. DUTTON
By
A. E. Merkell,
Attorney.

Patented Sept. 12, 1922.

1,429,130

UNITED STATES PATENT OFFICE.

ALFRED E. DUTTON, OF CLEVELAND, OHIO.

HEATING DEVICE.

Application filed July 9, 1921. Serial No. 483,460.

To all whom it may concern:

Be it known that I, ALFRED E. DUTTON, a citizen of the United States, resident of Cleveland, county of Cuyahoga, and State of Ohio, have invented new and useful Improvements in Heating Devices, of which the following is a specification, the principle of the invention being herein explained and the best mode in which I have contemplated 10 applying that principle, so as to distinguish it from other inventions.

My invention relates to heating devices and particularly to heating devices of a portable nature, electrically operated and 15 provided with means for producing a forced draft. The object of the invention is to provide a device of the above described character which is economical of construction and efficient in the performance of its function.

The said invention consists of means hereinafter fully described and particularly set forth in the claims. More specifically, my invention includes a heating device in which 20 a multiplicity of chambers are provided, adjacent chambers communicating with each other through the medium of restricted openings, these chambers being preferably superposed, the uppermost chamber communicating 25 by means of a duct, with the atmosphere, and the lowermost chamber communicating also with the atmosphere and associated with a fan for forcing atmospheric air through said chambers, baffle plates being 30 provided upon the interior of said chambers whereby a given amount of retardation of 35 the air current is produced in each chamber; the latter being each furthermore provided with an electrically heated element for heating 40 the air as it passes through or is retarded in said chambers. Other features of my invention will be hereinafter more fully described.

The annexed drawing and the following 45 description set forth in detail certain means embodying my invention, the disclosed means, however, constituting but one of the various mechanical forms in which the principle of the invention may be employed.

50 In said annexed drawing:

Figure 1 represents a front elevation of a portable heater embodying my invention.

Figure 2 represents a side elevation of same.

55 Figure 3 represents a section taken upon

the plane indicated by line III—III, Figure 1.

Figure 4 represents a section taken upon the planes indicated by lines IV—IV, Figure 3.

Figure 5 represents a diagram of the electrical connection.

The illustrated embodiment of my invention includes a housing 1 consisting of a front flat rectangular outer plate 2 of sheet metal and an inner insulating asbestos plate 3; and a back sheet metal plate 4 which is curved as at 5 forming an enlargement 6 of a rear compartment 7 of the housing, which compartment will be 70 hereinafter more specifically referred to.

The ends of the housing consist of asbestos plates 8 and the top and bottom of rectangular plates 9 and 10 respectively. The interior of the space enclosed by this housing is divided by a vertical partition consisting of the plate or asbestos lining 12.

Forming a frame for these plates are two forward channel bars 13—13, Figure 4, a bottom horizontal angle bar 14, vertical rear angle bars 15—15; and the plates are suitably secured to the frame thus formed by means of screws and angle clips in any desired or well known manner. Suitable legs 1' are provided as shown as well as a handle 9'.

The top of the compartment 7 communicates with the atmosphere by means of an opening 16 in which is placed a suitable screen 17 for filtering the air which passes 90 therethrough. The bottom of the compartment 7 is provided with an opening 18 through which projects an extension 19 formed upon the bottom of a casing 20 of a heating member which is placed within the 95 other compartment 21 formed by the partition plate 12.

The extension 19 opens into the lower part of the compartment 7 and located within said extension is a fan 22 operated by a 100 motor 23 which is located in the enlargement 6 of the compartment 7.

The casing 20 consists of two plates 24 and 25, each corrugated as shown, the rear plate being formed with the extension 19. 105 The number of corrugations are equal and they are similar in form so that when the plates are placed opposite each other as shown, chambers 26—26 are formed. Adjacent chambers communicate with each 110

other through restricted openings 27, the lowermost chamber being provided with the extension 19 as shown. The uppermost chamber communicates with a duct 28 through a similar restricted opening 27. This duct discharges into the atmosphere as shown, and extends substantially throughout the entire width of the heater.

The uppermost chamber is provided with

- 10 a baffle plate 29 which inclines downwardly and backwardly and is located adjacent to the uppermost opening 27. A similar baffle plate is placed near the other restricted opening 27 excepting the lowermost one.
- 15 Adjacent to the restricted openings 27 other than the topmost and lowermost openings, are upwardly and forwardly projecting baffle plates 30. These latter extend throughout the width of the chambers 26. The ends 20 of these chambers are formed by the end asbestos plates 8. The rear plate 25 is secured in place and to the adjacent plates by means of suitable screws and clips in any desired manner, its bottom resting upon 25 the bottom plate 10. The front plate 24 is also secured in a desired manner by means of suitable screws or clips and preferably has secured to it the front housing plates 2 and 3, so that when it is desired to have 30 access to the interior of chambers 26 the required screws may be loosened and the said front plate 24 with the attached plates 2 and 3 removed.

The motor 23 is connected with a suitable 35 source of electricity and a suitable switch 31, Figures 1 and 5, is provided for starting and stopping same.

Extending through each of the chambers 26 is a suitably supported insulated bar 32 40 which carries a resistance or heating wire 33. These wires are connected in parallel in the circuit as shown in Figure 5. The switch 31 is so arranged that these heating wires may be thrown into or out of the circuit in succession, as will be readily understood, so that for the purposes of heat regulation one or more of the heating wires may be made operative.

In use, the above described device operates 50 as follows:

The switch 31 is thrown to first close the motor circuit whereupon the fan operates and draws air through the opening 16 downwardly through the compartment 7 through 55 the extension 19 and upwardly through the chambers 26 from whence it finally emerges in a horizontal direction from the duct 28. The switch is then further closed, sending the current through the required heating 60 wires which becoming incandescent heat the air passing through said chambers. In so passing, however, this air comes into contact with the baffle plates which divert the current and retard its progress, thus creating 65 a circulation which permits the heating

wires to impart to the air, the required amount of heat. It will thus be seen that the heat of the heating elements may be efficiently applied and by regulating the speed of the motor and controlling the number of heating elements, the temperature of the emitted air may be regulated. Furthermore, the above described construction is such, that ready access may be had to the heating elements and substantially the entire construction may be made of sheet metal, and may be readily and economically assembled.

What I claim is:

1. In a heating device, the combination of 80 a housing having two compartments formed therein, the one compartment communicating at the top with the atmosphere and having an opening at the bottom; a casing in said other compartment communicating at 85 the top with the atmosphere and at the bottom, with said first-named compartment; electrical heating means in said casing; and means for forcing air from said first-named compartment through said casing. 90

2. In a heating device, the combination of 95 a housing having two compartments formed therein, the one compartment communicating at the top with the atmosphere and having an opening at the bottom; a casing in 100 said other compartment communicating at the top with the atmosphere and at the bottom with said first-named compartment, and consisting of two separate plates having oppositely disposed corrugations forming a 105 multiplicity of chambers, and separate end walls; electrical heating means located in each such chamber; and means for forcing air from said first-named compartment through said casing. 110

3. In a heating device, a heating member 115 consisting of the combination of a casing forming a multiplicity of chambers, adjacent chambers being connected with each other by means of restricted openings; a duct communicating with one end chamber by means of a restricted opening, and also communicating with the atmosphere; electrical heating means located in each such chamber; and means for forcing air through 120 such casing.

4. In a heating device, a heating member 125 consisting of the combination of a casing forming a multiplicity of chambers, adjacent chambers being connected with each other by means of restricted openings; a duct communicating with one end chamber by means of a restricted opening and also communicating with the atmosphere; of electrical heating means located in each such chamber; and means for forcing air through such casing; each of said chambers being provided with baffle plates adjacent to the 130 said restricted openings.

5. In a heating device, a heating member 130

consisting of the combination of a casing forming a multiplicity of chambers, adjacent chambers being connected with each other by means of restricted openings; a 5 duct communicating with one end chamber by means of a restricted opening, and also communicating with the atmosphere; electrical heating means located in each such chamber; and means for forcing air through 10 such casing; said chambers being provided with baffle plates located adjacent to the restricted openings which afford communication between adjacent chambers, the baffle plates adjacent to any one of said restricted 15 openings being located respectively upon opposite side thereof.

6. In a heating device, a heating member consisting of the combination of a casing

forming a multiplicity of chambers, adjacent chambers being connected with each other by means of restricted openings; a duct 20 communicating with one end chamber by means of a restricted opening, and also communicating with the atmosphere; electrical heating means located in each such chamber; and means for forcing air through such casing; said chambers being provided with baffle plates located adjacent to the restricted 25 openings which afford communication between adjacent chambers, the baffle plates of any one of said restricted openings being located respectively upon opposite sides thereof, such baffle plates being oppositely inclined.

Signed by me this 2nd day of July, 1921. 85
ALFRED E. DUTTON.
